CYLINDER HEAD AND COMBUSTION
CHAMBER CONSTRUCTION

Earl Ginn, North Muskegon, Harold Leslie Caselman, Muskegon, and Dana A. Campbell, Spring Lake, Mich., assignors to Continental Motors Corporation, Muskegon, Mich., a corporation of Virginia

Application April 9, 1942, Serial No. 438,244

2 Claims. (Cl. 123—191)

Our invention relates to an improved cylinder head construction and more especially to a cylinder head structure constructed for cooperative assembly with the cylinder block of an over-head valve internal combustion engine.

In this type of engine the combustion chambers are carried in the cylinder head structure and are arranged to over-lie the engine cylinders. In the present day high output engines it is necessary to employ large intake and exhaust valves and to provide as large a port area as is possible. It is difficult in engines of the character aforesaid to assemble extremely large valves as the engine structure is a limiting factor controlling the size of valves which may be used. The combustion chambers used with the engine aforesaid are usually circular or elliptical pockets formed in the head and the valves open inwardly of the combustion chamber and substantially axially inwardly of the engine cylinder. Consequently when using valves of maximum head diameter it will be observed that the peripheral edge of the valve usually is somewhat close to the side walls of the combustion chamber thereby restricting the flow of gases past the valve head at this zone of minimum clearance between the valve head and combustion chamber side wall.

An object of our present invention is to improve engine performance by providing a combustion chamber construction which facilitates a more uniform flow of gases past the valve heads, and which eliminates to a large degree the restrictions to gas flow in that part of the combustion chamber lying intermediate the valve head and the combustion chamber side wall.

Another object of our present invention is to construct an improved cylinder head structure which embodies a recessed portion for housing a plurality of sets of rocker arms, and which is so constructed as to drain oil accumulations from said rocker arm housing.

Other objects of our present invention pertain to various structural details described and claimed in particular detail hereafter.

For a more detailed understanding of our invention, reference may be had to the accompanying drawings illustrating a preferred embodiment of our invention, wherein like figures refer to like parts throughout the several views and in which:

Fig. 1 is a bottom plan view of the cylinder head structure embodying our invention,

Fig. 2 is a top plan view of the cylinder head structure,

Figs. 3, 4 and 5 are detail transverse sectional views through the cylinder head structure taken substantially on the lines 3—3, 4—4 and 5—5 respectively in Fig. 1.

Fig. 6 is an enlarged detail sectional view of the combustion chamber showing the valve partially open.

Fig. 7 is a similar view showing the valve wide open, and

Fig. 8 is a detail plan view of a combustion chamber showing the spark plug location.

The cylinder head structure herein illustrated by these several figures provides improved engine performance, and said head structure is preferably formed of a casting A which may be bolted in the usual manner to an engine cylinder block B by means of suitable bolts. The preferred construction embodies a structure overlying a plurality of cylinders 10 (see Figs. 2 and 5) and is provided with combustion chambers 11 cooperatively associated with each of the engine cylinders. The cylinder head is provided with intake and exhaust passages 12 and 13 respectively terminating in intake and exhaust ports 14 and 15, as more particularly shown in Figs. 6 and 7. The said ports have valve seats 16 fitted therein, the one illustrated being the intake valve seat. An intake valve 17 is operable to control this intake port 14 and it will be seen that same opens inwardly of the combustion chamber and substantially axially inwardly of the cylinder 10. As the valve moves off its seat the port area is increased at a rate allowing more and more gas to flow into the combustion chamber. The side walls 20 and 21 of said combustion chamber are constructed somewhat spherical in contour thus providing immediately for a maximum clearance between the recessed valve heads 22 and the adjacent combustion chamber wall, said clearance being increased as the valve opens, to provide more space or area through which the gases may flow without being restricted. The area of this space between the valve peripheral edge and the side wall of the combustion chamber is increased as the valve opens, at a rate preferably at least approximately as much as the rate of increase in the port area. Thus, it will be noted that this construction increases turbulence and facilitates the uniform distribution of the incoming gases in the combustion chamber thereby improving combustion and engine performance.

The upper portion of the cylinder structure is recessed as at 30, and the rocker arms are assem-

bled in this recess or pocket in a conventional manner, same being mounted on the conventional rocker arm shaft (not shown) supported in bearings which may be mounted on the bearing supports 31. The floor 33 of this recess or pocket 30 is sloped or inclined, as clearly shown in Figs. 3 and 4, to drain any oil accumulations to one side of the cylinder head. Preferably the low point of the floor 33 is in that region where the push rods 34 are operable. The cylinder head is provided with suitable openings 35 which support a push rod housing 36 and the oil accumulations are drained from the pocket or recess 30 into the push rod housing 36 and thence preferably into the oil return or scavenge line and subsequently into the crankcase of the engine.

The cylinder head structure provides a lateral inwardly recessed pocket 40 (see Fig. 5), which partially overlies the combustion chamber 11 and conveniently provides a spark plug pocket, the spark plug 46 being threaded into the tapped hole 41. Immediately below the pocket 40, the cylinder head is provided with a ledge 42 overlying the cylinder and a bolt 43 is threaded through a hole 44 in the ledge and secured to the engine block. The pocket 45 hereby provides a recess permitting easy access to be had to the head 45 of bolts 43 and to the spark plug 46.

It will be observed that the cylinder head structure herein illustrated facilitates economical engine manufacture and furthermore functions to provide for improved engine performance.

Although we have illustrated but one form of our invention and have described in detail but a single application thereof, it will be apparent to those skilled in the art to which our invention pertains, that various modifications and changes may be made therein without departing from the spirit of our invention or from the scope of the appended claims.

We claim:

1. A cylinder head construction for an overhead valve internal combustion engine comprising a combustion chamber overlying the engine cylinder and having substantially spherical shaped side walls and constructed substantially elliptical in plan, an intake valve opening inwardly of said combustion chamber, said spherical shaped combustion chamber walls adjacent the valves curved inwardly of the cylinder wall and providing an unrestricting clearance between said wall and valve periphery whereby to provide space for the flow of gas past said valve of an area at least as great as the valve opening area for all open positions of the valve.

2. A cylinder head construction for an overhead valve internal combustion engine, comprising a combustion chamber overlying the engine cylinder, valves opening inwardly of the combustion chamber and substantially axially inwardly of the engine cylinder, said valves being of maximum diameter and having peripheral edges lying closely adjacent to the side walls of the combustion chamber when closed, said combustion chamber side walls adjacent said valve peripheral edge curved inwardly of the cylinder walls and outwardly concave whereby to provide a space between the valve peripheral edge and the combustion chamber wall in juxtaposition thereto whereby to provide an unrestricting clearance therebetween increasing at a rate at least as great as the rate of increase of the space between the valve and its seat during the opening movement of the valve whereby to induce a substantially uniform flow of gas past the peripheral edge of said valve.
